CLAIM

The ornamental design for a closure, as shown and described.

DESCRIPTION

FIG. 1 is an isometric view taken from the top front and right side of a closure in the closed condition;

FIG. 2 is another isometric view thereof taken from the top rear and left side;

FIG. 3 is a front elevational view thereof;

FIG. 4 is a right side elevational view thereof, the left side elevational view thereof being a mirror image;

FIG. 5 is a rear elevational view thereof; and,

FIG. 6 is a top plan view thereof.

The undisclosed bottom view is unornamented, is not visible to the consumer when the closure is installed on a container (not shown), and forms no part of the claimed ornamental design.

In the drawings, the broken lines depict environmental subject matter only and form no part of the claimed design.
